UNITED STATES PATENT OFFICE.

KARL F. SNOW, OF CLEVELAND, OHIO, ASSIGNOR TO C. O. BARTLETT & CO.

DRIER.

SPECIFICATION forming part of Letters Patent No. 737,292, dated August 25, 1903.

Application filed February 13, 1902. Serial No. 93,877. (No model.)

To all whom it may concern:

Be it known that I, KARL F. SNOW, a citizen of the United States, and a resident of Cleveland, county of Cuyahoga, and State of Ohio, have invented a new and useful Improvement 5 in Driers, of which the following is a specification, the principle of the invention being herein explained and the best mode in which I have contemplated applying that principle so as to distinguish it from other inventions.

My invention relates to driers, one feature thereof particularly relating to that class of driers in which double side walls and a double bottom are used, which form a steam or heating chamber entirely separate from the drying-chamber. In driers of this character heretofore used the bottom and lateral inclosing portions of the drying-receptacle have been so constructed as to necessitate practically a rebuilding of the entire structure when it became necessary to remove the inner bottom plate when such removal was required by reason of the ultimate destruction of such plate resulting from continued use.

One object of my invention is hence to provide a construction whereby such inner bottom plate may be removed and replaced by another in an economical manner.

A second object of such invention is to provide means for effecting a continuous flow of atmospheric air over the contents of the drying-receptacle and a corresponding continuous withdrawal of such air and the gases or vapors emanating from such contents.

A third object is to provide improved means for agitating such contents to expose all parts thereof to the drying action of the receptacle-surface and of the air-current above mentioned.

The annexed drawings and the following description set forth in detail certain mechanism embodying the invention, such disclosed means constituting but one of the various mechanical forms in which the principle 40 of the invention may be used.

In said annexed drawings, Figure I represents a plan view of a drying apparatus embodying my invention; and Fig. II a vertical axial cross-section of same, showing parts in 45 elevation therein.

The drying-receptacle is preferably cylin-

drical in form, and its lateral inclosing portion A consists of two parallel plates a a , bolted at the top and bottom to the lateral surface of an upper separating frame-ring a' 55 and to a lower separating frame-ring a^2 , respectively. Studs a^3 connect the plates at intermediate points, as shown in Fig. II. The cover-plate a^4 of the receptacle is bolted to the upper surface of frame-ring a' . The lower frame-ring a^2 projects somewhat below the lower edges of the plates a a , as shown.

Two parallel bottom plates a^5 a^6 are bolted to the upper and lower surfaces, respectively, of a lower or bottom frame-ring a^6 , the edges 65 of the plates lying intermediately of the inner and outer edges of the ring, whereby a free strip or surface is left around and adjacent to the periphery of the ring. Said ring is bolted to the lower surface of frame-ring a^2 , such described free surface contacting such lower surface, as shown. Studs a^7 connect such two plates at intermediate points. The steam or heating chamber so formed is suitably connected with a source of 75 steam or heat supply.

When it is desired to replace the upper plate a^5 , it is only necessary to remove the bolts securing frame-ring a^6 , thereby disconnecting the entire bottom. The upper plates 80 may then be removed without disturbing the lower, such removal hence avoiding the necessity of disturbing the integrity of the lateral inclosing portion A.

In the top or cover plate a^4 are formed a 85 series of openings a^8 , controlled by valves a^9 . The openings are preferably of segmental form, as shown, and the valves of the well-known disk form having alternate segmental openings and webs, whereby by rotating the 90 disk about a central axis the openings a^8 may be varied in size and the admission of atmospheric air thereby regulated. At a suitable location in such top plate is formed another opening, which connects with an exhaust-blower B, Fig. I, rotated by suitable means. (Not shown.)

By opening the valve-openings and operating the blower a continuous influx of atmospheric air into the receptacle and over its contents is effected. Such current carries off the vapors or gases emanating from the drying 100

material and in consequence, as will be readily understood, greatly facilitates the drying operation.

Through the center of the top plate and mounted in suitable bearings c and c' is a vertical shaft C , rotated by means of suitable beveled gears c^2 and a driving-pulley c^3 , at the bottom of which are secured two horizontal diametrically-located arms c^4 c^4 . These arms revolve near to and parallel with the contiguous bottom plate, and their respective outer ends are provided with plows C' , having a horizontal lower edge c^5 . These plows carry material in their paths upwardly and discharge it toward the center of the receptacle, the arms c^4 c^4 constantly moving the material outwardly into such paths. The material is thus kept agitated, so as to give it all an opportunity to become subjected to the heated bottom and lateral receptacle surfaces and the air-current above, thus effecting the drying operation in a substantially uniform manner.

Other modes of applying the principle of my invention may be employed instead of the one explained, change being made as regards the mechanism herein disclosed provided the means stated by any one of the following claims or the equivalent of such-stated means be employed.

I therefore particularly point out and distinctly claim as my invention—

1. A drying-receptacle comprising the combination of a lateral inclosing portion, a bottom comprising an outer peripheral frame and two plates respectively secured to the upper and lower surfaces of such frame, the periphery of the upper plate terminating intermediately of the inner and outer edges of said upper surface whereby the peripheral portion of the latter is left free, said free surface being secured to the bottom surface of said lateral inclosing portion, and a suitable cover.

2. A drying-receptacle comprising the combination of a lateral inclosing portion consisting of an upper and lower frame and two plates secured respectively to the inner and outer portions of such frame; a bottom portion consisting of a frame and two plates secured to the upper and lower surfaces thereof respectively, the upper plate terminating intermediately of the inner and outer frame edges whereby a portion of the upper frame surface is left free, such free surface being secured to the under surface of the lower frame of the lateral inclosing portion; and a suitable cover.

Signed by me this 5th day of February, 1902.

KARL F. SNOW.
